Merchant and Walker

Patented Mar. 23, 1926.

UNITED STATES PATENT OFFICE.

NORMAN R. WALKER, OF AUSTIN, MINNESOTA.

HOLDER FOR MATCHES, TOOTHPICKS, STRAWS, AND THE LIKE.

Application filed November 21, 1924. Serial No. 751,261.

To all whom it may concern:

Be it known that I, NORMAN R. WALKER, a citizen of the United States, residing at Austin, in the county of Mower and State of Minnesota, have invented certain new and useful Improvements in Holders for Matches, Toothpicks, Straws, and the like; and I do hereby declare the following to be a full, clear, and exact description of the 10 invention, such as will enable others skilled in the art to which it appertains to make and use the same.

My invention relates to holders for matches, toothpicks, straws and the like, and 15 more particularly, to such a holder of the ejector type, and has for its object to improve the same in the several particulars hereinafter noted.

In the accompanying drawings, which 20 illustrate the invention, like characters indicate like parts throughout the several views.

To the above end, generally stated, the invention consists of the novel devices and combinations of devices hereinafter described and defined in the claim.

Referring to the drawings:

Fig. 1 is a plan view of the invention;

Fig. 2 is a view partly in side elevation and partly in central vertical section, taken 30 on the line 2—2 of Fig. 1;

Fig. 3 is a view principally in transverse section, taken on the line 3—3 of Fig. 2;

Fig. 4 is a detail view principally in section, taken on the line 4—4 of Fig. 3;

Fig. 5 is a perspective view of the ejector 35 blade; and

Fig. 6 is a detail view in transverse section showing a modification of the ejector blade.

The numeral 6 indicates a relatively heavy 40 cast base having formed therewith a relatively short hollow standard that is rectangular in cross section. Above the standard 7 is a cast head 8 having a depending skirt 9 that loosely telescopes over said standard. Carried by the head 8 is a receptacle 10 preferably formed from transparent glass and having in its top an elongated passageway 11. The sides of the 45 receptacle 10 converge to the passageway 11, and as shown, are preferably smooth, without any obstructions. Formed with the bottom of the receptacle 10 is a base 12 that is slidably mounted in a channel 13 in the head 8. The sides of the base 12

and the channel 13 have dove-tailed interlocking engagement, which holds the receptacle 10 against removal from the head 8 except by endwise sliding movement. A 50 pair of leaf springs 14, mounted in recesses in the bottom of the channel 13, engage the base 12 and lift the same into close engagement with the sides of said channel and hold the receptacle 10 firmly on the head 8. Within the receptacle 10 is a multiplicity of toothpicks X. It is, of course, understood that, in place of the toothpicks, matches may be held in the receptacle, or by making said receptacle longer, the same 55 may be used for holding straws, such as used at a soda fountain.

To remove the toothpicks from the receptacle 10, one at a time, there is provided an ejector blade 15 having in its upper edge a longitudinally extended groove 16 which is V-shaped in cross section, and said ejector blade 15, intermediately of the ends of said groove, is notched at 17 to afford a passageway. The size of the groove 16 is such as to hold only a single toothpick at a time, and the notch 17 is provided to permit the operator to easily pick up the toothpick held in the groove 16 from the ejector blade 15. Integrally 60 formed with the ejector blade 15 is a pair of flat depending legs 18, which extend through the skirt 9, standard 7, and have their lower end portions mounted in sleeve-like seats 19 formed in the base 6. Cotter pins 20 are provided for holding the legs 18 in their seats 19.

The ejector blade 15 is normally seated in a slot 21 formed in the base 12 and head 8 with its upper edge portion flush with the bottom of the receptacle 10, as best shown in Fig. 3. The head 8 is provided with a cross-tie member 22, which extends through the slot 21 in the head 8 and is straddled by the ejector blade 15 and legs 18. A pair of coiled springs 23, encircling the legs 18, are compressed between the head 8 and base 6 and normally hold said head and the receptacle 10 carried thereby to their raised positions. Normally, the ejector 65 blade 15 engages the cross-tie member 22 as a stop and limits the projecting movement of the receptacle 10.

To remove a toothpick from the receptacle 10, the operator, with one hand, presses 70 downward on the receptacle 10 against the

tension of the springs 23, which causes the skirt 9 to telescope over the standard 7 and engage the base 6 as a stop, as indicated by broken lines in Fig. 3. This movement of the receptacle 10 is such as to move below the upper edge portion of the ejector blade 15 so that the same projects through the passageway 11 and thereabove. During this compressing movement of the receptacle 10, the toothpicks X are carried downward therewith away from the ejector blade 15 and leaving only one thereof in the groove 16. This single toothpick is so held by the ejector blade 15 above the receptacle 10 that the operator can easily take hold of the same at the notch 17 and lift the same from the ejector blade 15. After the toothpick in the groove 16 has been removed, the operator releases the depressed receptacle 10, which is immediately returned to normal position by the springs 23.

Obviously, the standard 7 and skirt 9 completely encase the legs 18 and springs 23, and there is sufficient clearance between said skirts and standard to prevent friction or wear between the parts thereof. The legs 18, at their ends, are securely held in the base 6, and at their upper ends are connected by the ejector blade 15 and thereby securely hold the head 8. The hopper bottom of the receptacle 10 causes the toothpicks to roll to the center of said receptacle and over the upper end of the ejector blade 15 when the receptacle is returned to normal position, so that one thereof will fall into the groove 16 and be ejected the next time the holder is operated. The converging sides of the receptacle 10, aside from giving the receptacle an artistic appearance, make it extremely easy for an operator to pass his fingers along the sides thereof and take hold of a toothpick held on the ejector blade 15.

In assembling the several parts of the holder, the receptacle 10 is slid endwise into the channel 13 and then the legs 18 are inserted through the passage 11 in the receptacle and slot 21 in the base 12 and head 8 until the ejector blade 15 is stopped by the cross-tie member 22. The coiled

springs 23 are then telescoped onto the legs 18 and said legs inserted through the hollow standard 7 and into the seats 19. The cotter pins 21 are then inserted through aligned bores in a lug on the recessed bottom of the base 6 and legs 18, as best shown in Fig. 3. It will thus be seen that the several parts of the holder may be very quickly and easily assembled, and when once assembled are very rigid. The receptacle 10 is held against endwise sliding movement in the channel 13 by the ejector blade 15 and legs 18.

Referring now to the modification shown in Fig. 6, the numeral 24 indicates an ejector blade especially designed for dispensing two straws at a time and has a pair of parallel V-shaped grooves 25 for holding straws 26. The ridge 27 between the grooves 25 is in cross section in the form of an inverted V and extends considerably above the outer sides of the grooves 25 to prevent a third straw from being held between the two straws 26.

What I claim is:

1. A holder of the kind described comprising a base having a hollow standard, a head having a skirt forming an extension of said standard and adapted to be telescoped thereon, a receptacle carried by the head and having in its top a passageway, an ejector blade having a pair of legs extending through said skirt and standard and anchored to the base, and a pair of coiled springs encircling said legs and normally holding the receptacle raised, said ejector blade being arranged to move through the receptacle and its passageway when the receptacle is depressed against the tension of said springs, said hollow standard and skirt forming a constantly closed compartment for the legs and springs.

2. The structure defined in claim 1 in which the base is cast and provided with deep seats in which the lower end portions of the legs are seated and in further combination with fastening devices for securing the legs in their seats.

In testimony whereof I affix my signature.

NORMAN R. WALKER.
